UNITED STATES PATENT OFFICE.

CARL E. NOVILLE, OF NEW YORK, N. Y.

APPARATUS FOR SIMULATING MOVING PICTURES.

Application filed June 21, 1919, Serial No. 305,724. Renewed March 9, 1923.

To all whom it may concern:

Be it known that I, CARL E. NOVILLE, a citizen of the United States, residing at New York, in the county of New York and State 5 of New York, have invented new and useful Improvements in Apparatus for Simulating Moving Pictures, of which the following is a specification.

This invention relates to a method of 10 simulating moving pictures for advertising purposes and the like and is an improvement in my device shown in Letters Patent No. 1,288,145, of December 17, 1918.

In my patented device, I have found it 15 necessary to employ mechanism including lamps of distinguishing colors in order to mask the corresponding colors of the figures. In practice I have found this to be operative in a measure but impractical in a 20 degree due to the fact that the chemicals used in the coloring of the lamps are affected by the heat to such an extent that after the device has been in operation for a short length of time, it is practically useless.

One of the principal objects of this 25 improvement is to provide a device of the class described which comprises a translucent support having an image in color on one surface and a solid back ground of the same 30 color on the opposite surface with an image of a different color on the back ground in combination with means for intermittently casting light reflections through the member.

The color of the background will always 35 be the same as that of the image on the reverse side, but the shade may change according to the density of the material upon which the images are provided, though in most instances even the shade will be the 40 same. As an example of the relationship of the colors, if the image on the front of the support is in red, then the background on the opposite side will also be red, but if the support is of considerable density, the back- 45 ground will be of a correspondingly lighter shade, and the image on the back will be of an entirely different color as for instance black or blue.

Another object of the invention is to pro- 50 vide an article of manufacture in the nature of a translucent member carrying contrastingly colored images on opposite faces thereof and a solid back ground on one face of the same color with the image on the opposite 55 face which may be used in combination with

any single illuminating means which will contact with the back ground to visualize said images.

Another object of the invention resides in the simplicity and cheapness of the article 60 which will render it useful as an advertising device for all purposes.

With these and other objects in view the invention resides in the novel combination of elements which will be more fully described and pointed out in the appended 65 claims and illustrated in the accompanying drawings in which:—

Figure 1 is a plan face view of the translucent support showing an image in color 70 thereon.

Figure 2 is a face view of the support showing the solid colored back ground thereon.

Figure 3 is a similar view showing the 75 image in a distinguishing color superposed on the back ground.

Figure 4 is an exaggerated sectional view through the support illustrating diagrammatically the arrangement of the images and 80 back ground thereon.

Figure 5 is a diagrammatic view of one method of use of the device.

Figure 6 is a similar view of a modified 85 form.

Figure 7 is a diagrammatic view of a fur- 90 ther modification.

Figure 8 is a similar view of a still further modified form, and

Figure 9 is a similar view of another modi- 95 fication.

Referring to the drawings by characters of reference 10 designates a translucent element or support which may either be in the form of a single sheet of material of this 95 character or a tape upon which a plurality of advertising pictures are arranged. 11 designates an image in color which is printed or otherwise impressed on one face of the support. 12 designates a solid back ground 100 of a color the same as the image 11 and is arranged on the opposite face of the support 10. 13, designates an image which is superposed on the back ground and of a different color to the same.

In operation of the device, use is made of means for intermittently casting light reflections through the translucent support 10 from the side which is provided with the back ground in order to permit alternate 110

viewing of the images from the opposite side. The result of this operation is to simulate movement of the figure which is accomplished due to the fact that the images 11 and 13 are in different positions and when the figure 11 is viewed directly by the eye from an exterior source of light it is illustrated in one position but when light reflections are cast through the back ground, the figure 11 which is of a harmonizing color therewith will be obliterated and the figure 13 which is of a contrasting color, will be sharply defined and visible through the translucent support. The rapidity with which the illuminating means is adapted to be intermittently cast through the support will give the impression of movement to the figure, thus simulating life-like movements.

In the form illustrated in Figure 5, use is made of an electric lamp 14, which is included in a circuit provided with automatic flashing means conventionally illustrated at 15, for intermittently lighting the same and a plurality of translucent supports or elements 10 are arranged in a frame 16, which is supported from the electric fixture in which the lamp is secured.

Any well known form of "flasher" may be used, such as that which consists of a cylindrical shell constructed at one end to fit in a standard electric socket, and at the other end provided with means to support an electric bulb; and provided with resistance devices for effecting such thermal control of certain bars as to automatically effect a make and break of the current through the bulb.

In the form of use illustrated in Figure 6, the translucent support 10 is adapted to be pasted or otherwise secured against a show window glass 17 with the face carrying the image 11 outward. Use is made of an electric lamp 18 which is supported from a bracket 19 having suction means 20 for supporting the same on the glass 17. The lamp is adapted to lie directly behind the member 10 and is provided with flashing means conventionally shown for intermittently casting reflections through the member for the purpose hereinbefore described.

In the form illustrated in Figures 7 and 8, use is made of a translucent tape 21 having a back ground and images arranged thereon and automatic flashing means con-

ventionally illustrated for intermittently casting light reflections therethrough, arranged adjacent to the display opening in the casings 22, together with a means for intermittently moving the tape to expose the images.

The form illustrated in Figure 9 is a further adaptation of the use of the device and in this form a circular disk 23 is provided with a plurality of openings 24 over which the translucent members 10 are arranged. Use is made of an intermittent light casting unit 25 which is adapted to cast reflection through the members 10 separately when the disk is revolved on its shaft 26 through suitable operating means.

While I have illustrated and described an article of manufacture of the class described, and shown, several methods of carrying the same into use, I do not care to be limited to the exact details but desire to have it understood that such changes and alterations as fall within the scope of the claims may be resorted to when desired.

What is claimed as new is:

1. The combination of a translucent support provided with an image in color on one surface, a background of the same color on the opposite surface and an image of a different color on the background; means for illuminating said support; and means for intermittently rendering the first said means effective and ineffective as and for the purpose set forth.

2. An article of manufacture comprising a translucent support, an image in color on one surface, a background of the same color on the opposite surface, and an image of a different color on the background.

3. The combination of a translucent support provided with an image in color on one surface, a background of the same color as said image and on the opposite surface of said support from said image, and a second image in a color contrasting with the color of the first said image and on the same side of said support as said background, means for illuminating said support, and means for intermittently rendering the first said means effective and ineffective.

In testimony whereof I have affixed my signature.

CARL E. NOVILLE.
